SURGICAL INSTRUMENT

Charles Driest, Marlboro, N. J.; Cecilia Driest, executrix of said Charles Driest, deceased, assignor to Frederick Bishop, Marlboro, N. J.

Application April 29, 1935, Serial No. 18,848

7 Claims. (CL. 30—9)

This invention relates to what are generally known as surgical instruments including surgical knives or tools used in performing various types and kinds of operations by surgeons, dentists, 5 chiropodists and others as well as tools which may be used for manicuring purposes; and the object of the invention is to provide a tool of the class described consisting of a blade or tool supporting handle member with means on the handle member and on each of the tools for adapting one of a number of tools to the handle member and for retaining the same against displacement therefrom, whereby a single handle member may be utilized in conjunction with a plurality of 10 different types of blades, knives or instruments; a further object being to provide means for quickly attaching and detaching the blades with respect to the handle member; a further object being to provide a handle member for tools of the class 15 described which is formed from a rod or bar shaped to form parallel handle portions, the looped end of which is preferably flattened to form a tool or instrument end to the handle member, and the free end portions of the bar or rod being fashioned to collectively form the blade or 20 instrument engaging and supporting means; and with these and other objects in view, the invention consists in an instrument of the class and for the purpose specified, which is simple and 25 economical in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side view of a complete tool made 40 according to my invention.

Fig. 2 is an enlarged, sectional detail view of the blade end of the tool.

Fig. 3 is a cross section on the line 3—3 of Fig. 2.

Fig. 4 is a bracketed view involving independent figures, identified as *a*, *b*, *c*, *d*, *e*, *f*, *g* and *h*, each Figure 4*a*—4*h* showing a plan view of a blade which may be employed in the tool.

Fig. 5 is a view similar to Fig. 1 showing a slight modification; and,

Fig. 6 is a cross section on the line 6—6 of Fig. 5.

In carrying my invention into effect, I provide a tool supporting body or handle member 10 which is fashioned from a rod or wire bent to 55 form a crosshead loop 11 which is preferably flat-

tened if the wire is round in cross sectional form, and extending from the loop are substantially parallel handle portions 12 and 13 of sufficient length to provide the proper grip in the hand and to satisfy distinctive uses to which the invention may be applied. For example, in some cases, a wider or narrower spacing of the handle portions 12 and 13 will be found desirable. For the purpose of this description, the free end of the handle portion 12 will be termed a stationary 10 jaw 14, and the free end of the handle portion 13 a movable jaw 15, it being understood that in fact, both jaws 14 and 15 are movable, one with respect to the other, and sufficient spring action will be provided to normally maintain these jaws 15 in engagement with each other, especially with the construction shown in Figs. 1 and 2 of the drawing.

The jaw 14 is preferably flattened at opposite sides in the manner indicated in Fig. 3 of the drawing, and the inner edge is provided with an elongated groove or channel 16 which opens through the outer end of the jaw 14, and the free end of this groove terminates at a point inwardly of the jaw 15 as may be seen in Fig. 2 of the drawing. At the end of the jaw 14, the outer edge thereof is provided with a notch 17. The jaw 15 comprises an inwardly and angularly extending part, the free end of which has a V-shaped recess 18 which fits over and rests upon the flattened side walls of the jaw 14 as clearly seen in Fig. 3 of the drawing. The jaw 15 is also split as seen at 19 to receive one of a number of knives, blades or instruments 20. The handle portion 13 adjacent the jaw 15 is provided with a notch 21 arranged in alignment with the under surface 15*a* of said jaw 15, the surface 15*a* being beveled or inclined to form a beveled surface for the purpose of securing the tools 20 in position, as later described. The tool 20 shown in Figs. 1 and 2 of the drawing is in the form of a surgical knife.

In Fig. 4 of the drawing, I have shown at 20*a*, 20*b*, 20*c*, 20*d*, 20*e*, 20*f*, 20*g* and 20*h*, eight other types of tools which differ in contour but all of the tools have two commonly spaced and arranged elements, namely, projecting tongues 22 to engage the notches 17 and projecting lugs 23 to enter the recesses 21. The lugs have beveled upper edges 24 which cooperate with the beveled surfaces 15*a* of the jaws 15. Each of the tools 50 also has extending from the tongues 22 straight side edges 25 which are adapted to enter the channels 16 and to seat on the bottom walls of said channels in the manner clearly seen in Fig. 2 of the drawing, and the lower end portions of 55

the tools having the lugs 23 thereon will all be substantially of the same width and thickness to provide for the proper engagement of the jaw 15 therewith to tensionally support the tools in connection with the jaws 14 and 15.

In the use of my improved instrument, the tools 20—20^h are detachably coupled with the handle member 10 in the following manner. Assuming that the blade 20 is mounted in connection with the handle member as shown in Figs. 1 and 2, the thumb and one finger of one hand is placed upon opposite side surfaces of the jaw member 14, substantially centrally thereof and partially onto the tool supported therein, and the handle portion 13 is then engaged by the fingers of the other hand and forced outwardly away from the handle portion 12 against the spring tension thereof so as to disengage the jaw member 15 from the lower portion of the tool 20 after which the jaw 15 including the handle portion 13 is moved to one side of the tool and then the tool is engaged by the last end and withdrawn from the jaw 14 by movement longitudinally with respect to said jaw. Another tool 25 may be replaced by first passing the tool longitudinally of the jaw 14 with the edge 25 thereof in the channel 16 and until the tongue 22 engages the notch 17. The handle portion 13 is now engaged by the other hand to move the same outwardly a sufficient distance to permit the jaw 15 to pass over the lower portion of the tool, and in this operation, the beveled lower edge 15a of the jaw portion will engage the upper beveled edge 24 of the lug 23 and tend to draw the tool downwardly to securely hold the same in connection with the edges 14 and 15. In this connection, it will be understood that the spring pressure of the jaw 15 contributed thereto through the handle portion 13 will be upon the 40 blade. In other words, the beveled outer ends 18 of the jaw 15 do not necessarily engage the jaw 14.

In some types of instruments, it may be desirable to provide a means for securing the handle portions 12 and 13 together when the blade is in position. This may be accomplished in several ways. However, in Figs. 5 and 6 of the drawing, I have shown a coupling member 26 for this purpose which consists of two blades 26a and 26b secured together by screws or other devices 27. The side edges of the blades form channels 28 to receive the handle portions 12 and 13. In this construction, the handle portion 13 has an offset or cam portion 13a, note Fig. 5, in connection 55 with which the member 26 frictionally operates to secure the portions 12 and 13 against separation. Aside from the slight changes above referred to, the structure of the tool shown in Fig. 5 will be the same as that shown in Fig. 1, and like references will indicate like parts.

With a tool of the class under consideration, it will be apparent that various types of surgical or other tools or instruments may be supplied at a very nominal cost, thus effecting a material saving to the purchaser. While each physician or doctor may use several of the handle members as would be necessary in the performance of an operation, it will be apparent that a greater number of the tools or blades may be stocked and that such tools or blades may be replaced from time to time at a material saving. As a matter of fact, the cost of a complete tool made according to my invention would be considerably less than the cost of any tool of its kind now in use

where the tool and handle member are of unitary construction.

I am aware of the fact that efforts have been made in the past to provide handle portions with detachable and interchangeable blades, but by virtue of the manner of construction of these instruments, they have not proven to be of commercial success, largely due to the application and construction of the handle members employed, and the fact that screws or other devices were required in securing the parts together. 5

It is one of the distinctive features of my invention that no screws or like devices are necessary in providing the tool or blade engagement with the handle portion. Furthermore, the handle portion and tool are both of a simple construction and of such a structure as to facilitate sterilization thereof whenever desired. It will be understood that the illustration of the tools or blades herein shown is merely suggestive 20 of the possible methods of carrying the invention into effect, and furthermore, it will appear that the exact manner of engaging the blades with the jaw portions as well as the structure of the jaw portions may be varied within the scope of my 25 invention as is expressed in the claims.

It will also be apparent that by constructing a tool according to my invention, the handle and jaw portion thereof may be constructed of any type and kind of metal treated to give the same 30 the desired finish or polish, whereas the tools or blades may be constructed from the most suitable type of metal, and regardless of the expense of the latter, the same, by virtue of the simplicity and minuteness of the structure thereof can be 35 supplied to the purchaser at a very nominal cost.

Having fully described my invention, what I claim as new and desire to secure by Letters Patent, is:

1. A blade supporting member for instruments 40 of the class described comprising a body formed from an elongated strand of wire bent centrally to form a loop with rods extending from said loop in substantially parallel relation, the free end portions of said rods terminating in blade 45 supporting jaws movable relatively to each other, the loop end portion of said body being flattened to provide tensional engagement of said jaw ends, one jaw end being flattened slightly and provided on its inner surface with a longitudinal channel, the other jaw end comprising a part extending angularly in the direction of the first named jaw at a point adjacent the base of said channel, said last named jaw being split 50 longitudinally in the plane of the first named jaw, the split ends being adapted to normally rest upon the first named jaw at opposite sides of the channel therein, a member adjustably mounted on said rods for supporting the jaw ends 60 thereof in operative position, and one of said rods having a cam portion in connection with which said adjustable member operates.

2. An instrument of the class described comprising a handle member and a tool detachably 65 coupled with said handle member, the handle member consisting of two rods terminating at one end in jaw portions movable toward and from each other, one jaw portion having an elongated channel extending throughout the length 70 thereof and in which one side edge of the tool seats, means on said side edge of the tool engaging the free end of said jaw portion to limit the movement of the tool in one direction longitudinally of said jaw portion, the other jaw por- 75

- tion being angularly and laterally offset in the direction of the first named jaw portion and split to span the inner end of the tool, the inner end of the tool having a lug projecting in the 5 direction of said offset jaw portion and the front side of which is engaged by said offset jaw portion to retain the tool against displacement from said handle member.
3. An instrument of the class described comprising a handle member and a tool detachably coupled with said handle member, the handle member consisting of two rods terminating at one end in jaw portions movable toward and from each other, one jaw portion having an elongated 10 channel extending throughout the length thereof and in which one side edge of the tool seats, means on said side edge of the tool engaging the free end of said jaw portion to limit the movement of the tool in one direction longitudinally 15 of said jaw portion, the other jaw portion being angularly and laterally offset in the direction of the first named jaw portion and split to span the inner end of the tool, the inner end of the tool having a lug projecting in the direction of said 20 offset jaw portion and the front side of which is engaged by said offset jaw portion to retain the tool against displacement from said handle member, and said offset jaw portion and lug having interengaging beveled surfaces for moving the 25 tool longitudinally of the jaw portions in the coupling engagement of the second named jaw with said 30 tool, the free end of said offset jaw portion engaging the first named jaw portion when the tool is mounted in said jaw portion, and means slidably mounted on and frictionally engaging said rods inwardly of the jaw portions thereof to retain the jaw portions and tool against accidental displacement.
6. In an instrument of the class described, a handle portion in connection with which one of a number of different tools having a common coupling portion is adapted to be mounted, the coupling portion of each tool consisting of a projecting tongue arranged on one side edge of the tool intermediate its ends and a lug at the inner 20 end of the tool and projecting in the direction of the opposite side edge thereof, said handle portion comprising a single strip of material folded to form two relatively movable rod parts terminating at their free ends in tool engaging jaws, one of said jaws having an elongated channel in which the first named side edge of the tool is adapted 25 to seat with the projecting tongue engaging the free outer end of said jaw, the other jaw extending angularly and laterally in the direction of the first named jaw and being split to span the shank of the tool at the inner end thereof, the second named jaw engaging the front side of said lug at said inner end of the tool to move the tool longitudinally of the first named jaw to securely retain the tool against displacement from 30 both jaws, and the free ends of the split portion of the second named jaw overlying opposed 35 side surfaces of the first named jaw.
7. In an instrument of the class described, a handle portion in connection with which one of a number of different tools having a common coupling portion is adapted to be mounted the coupling portion of each tool consisting of a projecting tongue arranged on one side edge of the tool intermediate its ends and a lug at the inner 40 end of the tool and projecting in the direction of the opposite side edge thereof, said handle portion comprising a single strip of material folded to form two relatively movable rod parts terminating at their free ends in tool engaging jaws, one of said jaws having an elongated channel in which the first named side edge of the tool is adapted 45 to seat with the projecting tongue engaging the free outer end of said jaw, the other jaw extending angularly and laterally in the direction of the first named jaw and being split to span the shank of the tool at the inner end thereof, the second named jaw engaging the lug at said inner end of the tool to move the tool longitudinally of the first named jaw to securely retain the tool against displacement from both jaws, and the free ends of the split portion of the second named jaw overlying opposed 50 side surfaces of the first named jaw.
5. An instrument of the class described comprising a handle member and a tool detachably coupled with said handle member, the handle member consisting of two rods terminating at one end in jaw portions movable toward and from each other, one jaw portion having an elongated 55 channel extending throughout the length thereof and in which one side edge of the tool seats, means on said side edge of the tool engaging the free end of said jaw portion to limit the movement of the tool in one direction longitudinally of said 60 jaw portion, the other jaw portion being angularly and laterally offset in the direction of the first named jaw portion and split to span the inner end of the tool, the inner end of the tool having a lug projecting in the 65 direction of said offset jaw portion and the front side of which is engaged by said offset jaw portion to retain the tool against displacement from said handle member.
